RUBBER GLOVE

Mal Greenberg, Wichita, Kans., assignor to Meco, Inc., Wichita, Kans.

Filed Sept. 23, 1965, Ser. No. 87,148

Term of patent 14 years

(Cl. D3—11)

FIG. 1

FIG. 2

FIG. 3

FIG. 4

FIG. 5

FIG. 1 is a front elevational view of the palm side of a glove showing my new design;

FIG. 2 is an elevational view showing the back of the glove;

FIG. 3 is a side elevational view thereof;

FIG. 4 is a fragmentary enlarged view of the ornamentation thereof; and

FIG. 5 is a cross sectional view taken on the line 5—5 of FIG. 4.

The essential features of my design reside in the portions shown in full lines on the drawing.

I claim:

The ornamental design for a rubber glove, as shown and described.
